UNITED STATES PATENT OFFICE.

FRANK S. HAYDEN, OF HARRISONBURG, VIRGINIA.

CHICKEN RECORDER.

Application filed April 14, 1924. Serial No. 706,410.

To all whom it may concern:

Be it known that I, FRANK S. HAYDEN, a citizen of the United States, residing at Harrisonburg, in the county of Rockingham and State of Virginia, have invented a new and useful Chicken Recorder, of which the following is a specification.

The present invention is a chicken pedigree device or recorder for trap nests or the like which will give a record of each individual chicken entering the nest.

It is well known that numerous devices for accomplishing the same general purpose as this invention, that is, obtaining a record of laying hens, have been proposed, but it is the object of this invention to produce a simple and effective device of this kind which is more reliable and definite in its recordation of individual hens than like devices.

The invention briefly resides in a shiftable record sheet positioned at some point of entrance or exit of a nest upon which the hen will tread, the hen wearing on its foot a stamp having designating characters thereon which will impress its imprint on the recording sheet, the stamp being positioned under the foot of the hen directly under the leg thereof, where the greatest pressure will be exerted as the hen is forced to crouch as she enters a small passage or opening in the nest, the record sheet being shifted to present a fresh surface for other hens subsequently entering the nest.

The invention further resides in the sundry details of construction, and combination and arrangement of parts which will be described as the specification proceeds.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which show the preferred embodiment of the invention as at present devised,

Figure 1 is a sectional view taken through a trap nest equipped with the invention.

Fig. 2 is a fragmentary front elevation of a trap nest shown in Fig. 1.

Fig. 3 is a horizontal sectional view taken substantially on line 3—3 of Fig. 2.

Fig. 4 is a transverse sectional view taken substantially on line 4—4 of Fig. 3.

Fig. 5 is a fragmentary detail sectional view of a portion of the device illustrating a modified form of record sheet.

Fig. 6 is an underface of a hen's foot wearing a boot constructed in accordance with this invention and equipped with a record stamp.

Fig. 7 is a perspective view of a hen's foot wearing the boot, and

Fig. 8 is a transverse sectional view taken through the boot substantially on line 8—8 of Fig. 6.

Referring in detail to the drawings in which like characters denote like parts throughout the specification and drawings, 1 denotes a nest of any suitable type or construction equipped with an entrance opening 2 and an exit opening 3. Positioned inside of the nest and adjacent the entrance opening 2 is a suitable platform 4, over which a record sheet 5, preferably of paper or any other suitable material, is laid. This record sheet is to be stepped on by the hen wearing a boot 6, illustrated in Figs. 6, 7 and 8 of the drawings, equipped with a suitable marker or stamp having characters thereon which will denote the respective hen wearing the same.

This boot consists of a pad *a* of leather, cloth or other suitable material to lie under the ball of the foot directly under the leg of the hen, and having straps *b* extending from the edge of the pad *a* upwardly to lie between each toe of the hen, and connected to a bracelet *c* which is detachably fastened around the leg above the foot by any suitable means, such as the buckle *d*. To the outer face of the pad *a* is suitably attached a plate *e*, of metal or other suitable material, having sharp edged characters *f* thereon which will denote the wearer of the boot.

The entrance opening 2 may be of the usual size and dimension, however this open-

ing is partially closed by an inwardly vertically swinging door 7 cut out at its lower edge to form an opening 8 of considerably reduced dimensions than that of the entrance opening 2. The door 7 may be of any suitable construction of material so long as a reduced opening 8 is provided. The object of this construction is to provide an opening through which the hen can extend its head and shoulders and then finding that the door will give under forward pressure, will proceed into the nest, but will be forced to crouch due to the top edge *g* of the opening 8 engaging the back of the hen, as illustrated in Fig. 1. It is found that when the hen's foot flattens out the bottom of the foot directly under the leg engages the ground or floor and exerts considerable pressure thereagainst, because of the weight of the hen being on the ball of the foot, and additional weight exerted due to a crouching position.

It is to be understood that the record sheet 5 is so positioned on the platform 4 with relation to the door 7 as to permit the hen to step upon the sheet while in the crouched position. As the hen proceeds forward into the nest the door 7 will be swung upwardly so far on its pivot to move easily over the back of the hen without harm or injury to it, and after the hen is fully within the entrance the door 7 will swing closed by its own weight. The hen having stepped on the record sheet 5, has made a suitable impression thereon and has passed from the platform into the body of the nest 9 where she lays an egg. By reason of the door 7 being hung to swing inwardly only, the hen will be forced to pass from the nest through the exit opening 3.

The exit opening 3 is of the usual dimensions and is partially closed by a vertically outwardly swinging door 10 which is of the same general constructions as the door 2, but can be modified as desired. The purpose of the door 10 is to cause the hen to swing it outwardly as it passes from the nest and to shift the recording sheet 5 to present a fresh surface at the entrance opening 2.

In some forms of this invention it may not be desirable or necessary to shift the record sheet 5 but on poultry farms where large numbers of chickens are raised, it is found that this is desirable.

The record sheet 5 may be of wax or soft material which will receive an impression from the stamp, or it may be a paper disposed over an inking ribbon 11 (as shown in Fig. 4), or over a suitable carbon sheet 12, shown in Fig. 5.

In the construction shown in Figs. 1, 3 and 4, both the record sheet 5 and the inking ribbon 11 are shifted as the hen passes through the exit opening 3. To accomplish this a roll of record paper is supported on the bearings 13 and passes upwardly through a suit-

able slot 14 in the platform 4 and thence along the platform in front of the opening 2 through a slot 15 and then down between feed rollers 16 and 17. The inked ribbon is likewise supported on bearing brackets 18 and passes up through a slot 19 and extends co-extensively with and under the recording sheet 5, hence through the slot 15 and is likewise fed by the rollers 16 and 17, and is rewound on a spool 20 held in yieldable engagement with the roller 17, by a spring 21.

Motion is imparted to the feed roll 17 by a cable 22 having one end secured to the exit door 10 and passing over suitable pulleys to a drum 23 upon which the other end of the cable is wound. The drum 23 is loosely mounted on the shaft 24 which supports the feed roller 17 and with which the roller 17 is fast. A torsion spring 25 constantly exerts a yielding tension on the drum 23 to maintain the cable 22 taut and for winding the same thereupon.

A ratchet wheel 26 is fast on the shaft 24 and is engaged by a pawl 27 rotatable with the drum 23. The arrangement of these parts is such that when the door 10 is swung upwardly by the hen passing out of the nest, the drum 23 is rotated in the direction of the arrow, shown in Fig. 4, the pawl 27 will engage the ratchet 26 and rotate the feeding roll 17 which, by reason of its frictional contact with the roller 16, will shift the record sheet and the ribbon 11 on the platform a desired degree.

It is also well within the purview of the invention to substitute for the ribbon roll 11 a stationary carbon sheet 12, shown in Fig. 5.

To protect the record sheet 5 a suitable cover 28 may be provided having an opening 29 therein arranged directly in the path of movement of the hen entering through the opening 2, thereby reducing the area of the record sheet which will be exposed.

In order to lock the entrance opening against the admission of other hens while the nest is being occupied, a suitable latch means is employed which will be rendered effective by the movement of the door 7 and ineffective by the exit of the hen through the opening 3. To this end a latch bar 30 is slidably mounted on the cover 28, or other suitable portion of the nest, to have a movement toward and away from the door 7. The end of the bar 30, adjacent the door 7, carries a resilient detent 31 to be moved in position to be engaged by the door and hold it in locked position, by a spring 32 acting on the latch bar to slide the same in its guides 33. The latch bar carries a rigid stop member 34 positioned to be engaged by a detent 35, to hold the latch bar 30 in its normal ineffective position and against the action of the spring 32. The detent 35 is actuated by a bell crank lever 37 having one end suitably connected thereto to shift it out

of the path of the stop 34, and the other end thereof having a projecting arm 38 positioned to be engaged by the inward swinging movement of the door 7. The sliding 5 latch bar 30 is connected at its inner end by a cable 36, or other suitable means, to the outwardly swinging exit door 10. Assuming that a hen has passed out of the nest and swung the door 10 to its dotted line position, 10 a suitable pull is exerted on the cable 36 to draw the latch bar 30 against the action of the spring 32 to the full line position shown in Fig. 1. In this position, the detent 35 will engage the stop 34 and hold the latch bar in 15 its ineffective position, whereby the door 7 is free to swing inwardly to the dotted line position shown in Fig. 1. Now assuming that a hen enters, moving the door 7 to the dotted line position, the door will engage 20 the projecting arm 38 of the bell crank lever and move the same to the dotted line position, which will raise the detent 35 out of engagement with the stop 34 and permit the spring 32 to move the latch bar toward the 25 doorway 2 to locking position, this movement of the bar 30 being limited by the engagement of the stop 34 with the guide 33. After the hen has passed into the nest the door 7 will gravitate to the full line vertical 30 position, and in so returning the extension 39 therein will engage the resilient detent 31, depress and pass the same, whereby the detent 31 will lie on the inside of the extension 39 in its path of movement, to maintain 35 the door locked against the admission of another hen, until the hen occupying the nest has passed out and operated the door 10 which in return actuates the latch bar 30 to ineffective position, as above described. 40

The relative position of the extension 39 and detent 31 is such, in their locked position, that inward pressure on the door 7 will not be in the direct line of movement of the 45 detent 31 or the bar 30, but substantially angularly thereto, and therefore cannot move the bar against the pressure of the spring 32. A door 40 is provided in front of the nest to permit access to the record sheet 5 fed through the rollers 16 and 17 in order 50 that the record may be obtained daily.

It is to be understood that the construction herein shown may be varied in such manner as permitted by the claims without departing from the spirit thereof, and it is also within the purview of the invention to employ rollers and antifriction elements as may be necessary and required to reduce friction between the operating parts.

Having described the invention in the form it is at present devised, and in what manner the same is to be performed, what is claimed as novel and upon which it is desired to secure Letters Patent, is:

1. A register for chicken nests comprising 53 a nest having entrance and exit openings, a

shiftable recording sheet arranged at one of said openings to be stepped on by a chicken, means for maintaining the entrance closed against ingress and egress after a chicken has passed into the nest, means at the exit 70 opening to prevent ingress, an actuating means operated by the exit of the chicken for shifting said record sheet after the latter has received said impression thereon and for releasing said closure means at the entrance 75 opening.

2. A nest for chickens having an entrance and exit opening, closure means at said openings, a shiftable recording sheet arranged at the entrance opening to be stepped on by 80 the chicken, means for shifting the sheet, comprising a feeding mechanism and an operating connection between said mechanism and the closure at the exit.

3. A nest for chickens having entrance 85 and exit openings, a record sheet arranged at the entrance opening to be stepped on by the chicken, a stamper worn by the chicken's foot, means for shifting the sheet and actuated by the exit of the chicken from the 90 nest, doors arranged at said openings, the door at the entrance opening being cut away to permit the partial entrance of the chicken and to swing vertically under the advance of the chicken in the nest, whereby the chicken 95 is caused to crouch and exert greater pressure on the stamper and effect a clear impression on said record sheet, said actuating means consisting of feed rollers, a spring drum, a pawl and ratchet connection between 100 said drum and rollers, and a flexible connection between said exit door and said drum and normally held taut by said drum.

4. A nest for chickens as set forth in claim 3 further characterized by means for 105 automatically locking the entrance door against inward movement after the chicken has entered the nest, and a connector between said means and said exit door and actuated by the movement of said door to render said 110 locking means ineffective.

5. A nest for chickens having entrance and exit openings, doors for said openings normally urged to closed position, means for automatically locking the entrance door against inward movement after a chicken has passed into the nest comprising a latch having a yieldable detent portion normally urged in the path of movement of the door, another detent for holding the latch in ineffective position and actuated by the open 115 of said entrance door to release said latch, and an operable connection between said exit door and latch for moving the latter out of the path of the entrance door and to position to be held by said second detent.

6. A nest for chickens having an entrance opening, a record sheet arranged at the entrance opening to be stepped on by the chicken, a stamper to be worn by the chick- 120

en's foot, a door partially restricting said opening and to swing vertically under the advance of the chicken into the nest, whereby the chickens is caused to crouch and exert greater pressure on the stamper.

7. A nest for chickens having entrance and exit openings, a movable member at said exit opening, a record sheet arranged adjacent the entrance opening, a stamper to be worn by the chicken's foot, means for shift-

ing said sheet, comprising feed rollers to move the sheet, and a step-by-step actuator connected to said rollers, and a connection between said actuator and movable member at the exit opening, whereby said actuator is 15 operated as a chicken passes from the nest therethrough.

In testimony whereof I have hereunto set my hand.

FRANK S. HAYDEN.
